DISPLAY STAND

John D. Miller, Clifton, N. J.

Application January 12, 1956, Serial No. 39,698

Term of patent 14 years

(Cl. D80—10)

Fig. 1.

Fig. 2.

Fig. 1 is a side view of the display stand, and

Fig. 2 is a top plan view partly in section on the line II—II of Fig. 1, showing the middle cruciform tray displaced 45° with respect to the upper tray; the lowest tray being precisely eclipsed by the upper one in this view.

The dominant feature of my design resides in the full line portion of the drawing.

I claim:

The ornamental design for a display stand, substantially as shown and described.
